UNITED STATES PATENT OFFICE.

VINCENT M. YOUNG, OF MASON, IOWA.

COMBINATION ROTARY LOCK.

1,401,228.

Specification of Letters Patent. Patented Dec. 27, 1921.

Application filed July 30, 1920. Serial No. 399,978.

To all whom it may concern:

Be it known that I, VINCENT M. YOUNG, a citizen of the United States, residing in the city of Mason and State of Iowa, have 5 invented new and useful Improvements in Combination Rotary Locks, of which the following is a specification, reference being had to the accompanying drawings.

This invention pertains to rotary locks, 10 designed for locking any rotary element of a machine, such as the adjustment knobs of the Holley or Kingston style of carbureters, or the steering wheel of any automobile.

The object is to provide a simple, efficient 15 and durable form of lock of this character, which may be readily attached to the element to be locked, and having combination elements whereby the lock may be instantly operated without the use of keys.

20 In the drawings:

Figure 1 is a perspective view showing the lock attached to a carbureter knob.

Fig. 2 is a top plan view.

25 Fig. 3 is a horizontal section on the line 3—3 in Fig. 2.

Fig. 4 is a side elevation showing the lock plate released.

Fig. 5 is a detail of the case.

Fig. 6 is a detail of the lock plate.

30 Fig. 7 is a detail of the combination or key plate.

Fig. 8 is a detail of one of the lever and push rod assemblies.

Fig. 9 is a sectional detail of the lever 35 ring, showing the method of mounting the rocking levers thereupon.

The invention consists of a suitable hollow, cylindrical case 1, with a closed top 2 pierced with a central lock stem hole 3, and 40 with a circle of holes 4. The bottom of the case 1 is open as shown at 5 and a key plate 6 is rigidly mounted within the case adjacent the open bottom end thereof, and parallel to the top 2. The key plate 6 is pierced 45 with two circles of key holes 7 and 8, the inner circle of holes 7 being alined with the holes 4, and has a central lock stem hole 9 alined with hole 3. A lever ring 10 is rigidly mounted in the case immediately above the 50 key plate 6, being supported by studs 11.

A recessed, annular seat 12 is formed around the open end of the case 1, and a circular lock plate 13 is adapted to seat therein. This plate 13 is formed with two circles 55 of sockets 14 and 15, alined respectively with the circles of key holes 7 and 8. A

lock stem 16 is permanently attached to the center of the lock plate 13 and is then slidely passed up through the holes 9 and 3. A handle 17 is fixed at the upper end of the 60 stem 16.

A plurality of push rods 18 are slidely passed through the holes 4, and the lower ends thereof have threaded sockets 19 adapted to receive the threaded keys 20. Springs 65 21 normally hold the rods 18 in their uppermost position, and in this position the lower ends of the keys 20 will just clear the upper face of the key plate 6. When depressed, however, the keys 20 pass down through the 70 key holes 7 and into the sockets 14, thus locking the lock plate 13 against rotation. Rocking levers 22 are pivotally mounted at 23 upon the lever ring 10, and the inner ends of these levers 22 are pivoted at 24 to the 75 lower ends of the rods 18, while the outer ends are provided with threaded sockets 25 to receive the threaded keys 26, adapted to engage the keyholes 8 and the sockets 15, thus locking the lock plate 13 against rotation. The keys 20 and 26 are so proportioned and mounted, that when the push rods 18 are in elevated position the keys 20 will clear the plate 6, while the keys 26 will pass through the plate 6 and into the sockets 80 15; on the other hand, when the rods 18 are in depressed position the keys 20 will pass through the plate 6 and enter the sockets 14, while the keys 26 will then clear the plate 6. In either case and without further 85 provision, the lock plate 13 would stand locked against rotation. Now in order to form combinations of the push rods 18 to permit the lock plate 13 to be rotated, all of the keys 20 and 26 are unscrewed from their sockets, when of course the lock plate 13 may be freely rotated by the handle 17. The addition of a key 26 to a rocking lever 90 22 makes it necessary to depress the corresponding rod 18 in order to rotate the 100 plate 13. In addition of a key 20 to a different rocking lever 22 makes it necessary to leave that lever in its normal, elevated position in order to rotate said plate.

Thus it is evident that by adding other 105 keys 20 and 26 to other and different rocking levers 22, various combinations can be made for unlocking the lock plate 13 for rotation, and also that these combinations may be changed as desired. The only condition 110 is that where a key 20 is added, the companion key 26 must be omitted. Also the

keys 20 when in place, must be left undis-
turbed in their elevated positions, as if de-
pressed they will act to lock the device.
Finger tabs 27 are fixed at the top ends of
5 the push rods 18, and numerals or letters
represented thereon, as shown, to facilitate
the formation and recollection of combina-
tions. The knob 28 or other rotatable ele-
ment to be controlled, is rigidly attached to
10 the lock plate 13.

While I have herein described a certain
specific method of construction and assem-
bling the elements of my invention, it is un-
derstood same may be varied in minor de-
tails, not departing from the spirit of my
15 invention as defined in the appended claim.

What I claim to be new and patentable is:

A combination rotary lock of the character
described, comprising a hollow, cylindrical
20 case, closed at the top end and having a
recessed, annular seat formed around the
open end of the case; a key plate rigidly
mounted within the case adjacent the open,
bottom end and parallel to the top; a lever
25 ring rigidly mounted in the case immediately
above the key plate; a circular lock plate
adapted to seat in the recessed open end of
the case; central and vertically alined lock
stem holes in the top and key plates; a lock

stem permanently attached to the center of 30
the lock plate and extended up through said
lock stem holes in the key and top plates;
an inwardly disposed circle of holes in the
top plate; an inner circle of alined key holes
35 in the key plate; an inner circle of alined
sockets in the lock plate; an outer circle
of key holes in the key plate; an outer circle
of alined sockets in the lock plate; push
rods slidingly extended down through the
40 top holes, and having threaded sockets in
their lower ends; threaded keys adapted to
screw into said sockets and to pass through
the holes in the key plate and down into
the inner circle of sockets in the lock plate;
rocking levers pivotally mounted on the lever 45
ring, and their inner ends pivotally engag-
ing the lower ends of the push rods, and
having threaded sockets in their outer ends;
threaded keys adapted to engage said sockets
50 and to pass through the holes in the key plate
and down into the inner circle of sockets in
the lock plate; and springs to normally hold
the push levers in their uppermost position.

VINCENT M. YOUNG.
